UNITED STATES PATENT OFFICE

RUDOLPH RUZICKE, OF DOBBS FERRY, NEW YORK

DESIGN FOR COVER PAPER

Application filed January 28, 1932. Serial No. 42,656. Term of patent 7 years.

To all whom it may concern:

Be it known that I, RUDOLPH RUZICKE, a citizen of the United States, residing at Dobbs Ferry, Westchester County, State of New York, have invented a new, original, and ornamental Design for Cover Papers, of which the following is a specification, reference being had to the accompanying drawing, forming part thereof.

The figure is a plan view of a section of cover paper bearing my design, such paper being intended for use especially in covering boxes, lining envelopes, and the like.

I claim:

The ornamental design for cover paper, substantially as shown and described.

RUDOLPH RUZICKE.
